AIR-COOLING DEVICE

Donald R. Williams, Dearborn, and Robert "B" Kizer, Melvindale, Mich.

Application December 28, 1948, Serial No. 67,723

9 Claims. (Cl. 62—129)

1

Our invention relates to a new and useful improvement in an air cooling device adapted for use in circulating and cooling air as it is circulated.

It is an object of the invention to provide a device of this class which will be simple in structure, economical of manufacture, durable, compact, and highly efficient in use. Another object of the invention is the provision of an air cooling device of this class in which a cooling liquid may be vaporized and the vapor subjected to a condensing by circulating through a cooling container while at the same time using the cool circulating air for cooling the liquid which circulates through the container.

Another object of the invention is the provision of a device of this class which may be operated with slow speed and yet produce a maximum of cooling.

Another object of the invention is the provision in a device of this class of a circulating mechanism which may be adjusted to various volumes and capacities.

Another object of the invention is the provision of an air cooling structure which will be sanitary and safe.

Other objects will appear hereinafter.

It is recognized that various modifications and changes may be made in the detail of structure without departing from the invention, and such are within the contemplation of this specification.

Forming a part of this specification are drawings in which:

Fig. 1 is a diagrammatic view of the invention illustrating certain parts in section,

Fig. 2 is a slightly enlarged fragmentary view taken on line 2—2 of Fig. 1,

Fig. 3 is a slightly enlarged sectional view taken on line 3—3 of Fig. 1,

Fig. 4 is a slightly enlarged fragmentary sectional view taken on line 4—4 of Fig. 1,

Fig. 5 is a fragmentary diagrammatic view illustrating the application of the invention to a vehicle,

Fig. 6 is a fragmentary sectional view, slightly enlarged, taken on line 6—6 of Fig. 1.

In the drawings we have illustrated the invention comprising a housing embodying the walls 9, 10, 11, 12, and 45. Formed in the wall 11 is an opening 13 which is closed by a suitable screen 14, communicating with which is a conduit 15, which communicates with the interior of the box or housing 16 to provide an inlet for a blower 17 communicating with the box or housing 16 to pro-

2

vide an outlet and connected to a suitable nozzle 18, which is positioned in an opening 19 formed in the wall 12.

Positioned within the box or housing 16 is a container 20, communicating with which is an inlet delivery pipe 21, which leads into the valve housing 22, in which is positioned a valve 23 controlled by the rockable beam 24 pivotally mounted on the standard 26, this beam 24 being provided with a float 25 so that liquid contained within the container 20 will serve to rock the beam 24 and move the valve 23 into closing position when the liquid has risen to a predetermined height. An outlet pipe 27 communicates with the valve housing 22 and also with a header or manifold 28, leading from which there is a plurality of tubes 29 each having a constricted portion 30 provided intermediate its ends and provided with a baffle 31. These tubes 29 communicate with the interior of the container 20 through the bottom thereof.

The inlet delivery pipe 21 communicates with a coil 32 positioned in the interior 74 of the container 33, and this coil 32 communicates by the pipe 34 through the check valve 35 with one end 36 of a cylinder 36a, in which is slidably mounted a piston 37. The pipe 34 also communicates with the opposite side 39 of the cylinder 36a through the check valve 38. A vapor outlet pipe 40 communicates with the container 20 adjacent the upper end thereof and through the check valve 41 with the side 36 of the cylinder and through the check valve 42 with the side 39 of the cylinder 36a.

The piston 37 is provided with a piston rod 43.

As shown in Fig. 2, the piston rod 43 slidably projects through collars 44 carried by the brackets 46 which are mounted on the wall 45. An opening 47 is provided in the rod 43 through which extends a rod 48. The rod 48 projects, intermediate its ends, through a sleeve 49 in which is provided a plurality of openings 50, as shown in Fig. 1, and through one of these openings, as shown in Fig. 4, is extended a bolt 51, which also extends through the bight 52 of a bracket 53 mounted on the wall 45 so that the rod 48 is thus pivotally mounted on the bolt 51.

This rod 46 extends through the block 53 in which is formed a pocket 54 in which engages a nut 56 on the studs 55. This block 53 is rotatable on the stud 55, and the rod 48 is slidable in the block 53. This stud 55 is fixedly mounted on a suitable bracket 57 which is connected to the links 58 of a chain belt 59 which passes around the sprocket wheel 60 and the sprocket wheel 61.

This sprocket wheel 61 is driven through the sprocket wheel 63 and the belt 62, as shown in Fig. 1, by the sprocket 64, which is driven by an electric motor 65.

The pipe 40, as shown in Fig. 1, is provided with a by-pass 66 which leads into a pressure switch housing 67 to control the circuit to the motor 65, and in this circuit 68 is also mounted a hand-operated switch 69.

An outlet delivery pipe 70 communicates with the container 33 and connects to a pump 71. This pipe 70 then communicates or is turned into a coil 72 positioned within the box or housing 16 in the path of the air which is passing through the box. The opposite end of the coil 72 is connected by the pipe 73 with the interior 14 of the container 33. A thermostat having a part 75 projecting into the container 33 is mounted on the outer surface of the container 33, this thermostat 76 serving to control the circuit 78 to the electrically-driven pump 71.

In Fig. 5 we have shown an application of the device wherein the box embodying the side wall 9 is mounted on the back 79 of a seat 80 positioned rearwardly of a steering wheel 81. This is merely to illustrate an application of the invention, and merely illustrates one use of it.

In use, a certain quantity of volatile liquid such as methyl chloride is deposited in the container 20 and the motor 65 is set into operation so as to reciprocate the piston 37. As the piston reciprocates, the vapor in the upper part of a container 20 will be drawn off through the pipe 40, and as the piston 37 moves to the left, this vapor will pass through the check valve 41 into the section 36 of the cylinder 36a, the check valve 35 being moved to closed position. At the same time, the check valve 38 will be open and the check valve 42 will be closed. Upon the opposite stroke, that is, when the piston 37 moves to the right, the vapor through the pipe 40 will pass through the check valve 42 into the side 39 of the cylinder, and in this movement the check valve 41 will be closed, as will likewise the check valve 38, while the check valve 35 will be open. The vapor drawn into the section 36 of the cylinder will then be forced through the pipe 34 and through the coil 32, where this vapor will become cooled and condensed so that it may be delivered in a cooled condition to the container 20. On the reverse stroke, the vapor drawn into the section 39 will be expelled through the check valve 38 and pass through the cooling coil 32. Contained within the container 33 is a quantity of cooling material such as water or the like, which serves to maintain the coil 32 in a cooled condition. This cooled liquid will pass through the pipe 21 to the valve housing and through the pipe 27 into the header 28, and through the tubes 29 into the container 20, the baffle members 31 serving as fins. The air blown across these tubes will become cool, so that as it issues from the nozzle 18 it will be cool.

In this manner, it becomes possible to cool a large quantity of air depending upon the capacity of the blower 17.

Should the pressure of the vapor in the container 20 or the line 40 become excessive, this would operate the pressure switch 67 so as to set the motor 65 into operation and draw off the vapor from the container 20. It is possible that it will not be necessary to maintain the circulation of the coolant which is in the container 33 constantly, and this will be controlled by the thermostatic switch 76 so that the circulation of

the coolant through the coil 72 may thus be determined.

It is believed obvious that by moving the bolt 51 to various openings 50, the "throw" of the rod 48 may be varied, thus shortening or lengthening the stroke of the piston 37 and thus increasing or decreasing the amount of fluid which is being circulated by means of the piston 37.

The mounting of the rod 48 upon the belt 59 is such that the block 53 will ride around the sprockets 60 and 61 without interference.

In this manner, we have provided an air cooling device which is believed to obtain the various advantageous features herein set out as well as others and which has proven most efficient as an air cooling mechanism.

What we claim as new is:

1. In an air cooling device of the class described, comprising: a housing having an air inlet and an air outlet; a container positioned within said housing adapted for the reception of a volatile liquid; a manifold; a plurality of tubes establishing communication with said manifold and with said container through the bottom thereof; a valve housing positioned within said container; an outlet conduit communicating with said valve housing for conducting liquid to said manifold; an inlet conduit for conducting liquid into said valve housing; a valve in said housing; a rockable beam adapted upon rocking in one direction for opening said valve; and a float mounted on said beam and adapted upon rising of liquid in said container to a predetermined height for rocking said beam in the opposite direction to close said valve.

2. In an air cooling device of the class described, comprising: a housing having an air inlet and an air outlet; a container positioned within said housing adapted for the reception of a volatile liquid; a manifold; a plurality of tubes establishing communication with said manifold and with said container through the bottom thereof; a valve housing positioned within said container; an outlet conduit communicating with said valve housing for conducting liquid to said manifold; an inlet conduit for conducting liquid into said valve housing; a valve in said housing; a rockable beam adapted upon rocking in one direction for opening said valve; and a float mounted on said beam and adapted upon rising of liquid in said container to a predetermined height for rocking said beam in the opposite direction to close said valve; and a vapor outlet pipe communicating with said container above the liquid level thereof for conducting vapors from said housing.

3. In an air cooling device of the class described, comprising: a housing having an air inlet and an air outlet; a container positioned within said housing adapted for the reception of a volatile liquid; a manifold; a plurality of tubes establishing communication with said manifold and with said container through the bottom thereof; a valve housing positioned within said container; an outlet conduit communicating with said valve housing for conducting liquid to said manifold; an inlet conduit for conducting liquid into said valve housing; a valve in said housing; a rockable beam adapted upon rocking in one direction for opening said valve; a float mounted on said beam and adapted upon rising of liquid in said container to a predetermined height for rocking said beam in the opposite direction to close said valve; and a vapor outlet pipe communicating with said container

above the liquid level thereof for conducting vapors from said housing; a cylinder; a piston reciprocating in said cylinder, said vapor outlet pipe communicating with said cylinder at opposite sides of said piston; and a check valve in said vapor outlet pipe and said cylinder at each side of said piston for controlling the flow of fluid into said cylinder upon movement of said piston in either direction relatively to said cylinder.

4. In an air cooling device of the class described, comprising: a housing having an air inlet and an air outlet; a container positioned within said housing adapted for the reception of a volatile liquid; a manifold; a plurality of tubes establishing communication with said manifold and with said container through the bottom thereof; a valve housing positioned within said container; an outlet conduit communicating with said valve housing for conducting liquid to said manifold; an inlet conduit for conducting liquid into said valve housing; a valve in said housing; a rockable beam adapted upon rocking in one direction for opening said valve; and a float mounted on said beam and adapted upon rising of liquid in said container to a predetermined height for rocking said beam in the opposite direction to close said valve; and a vapor outlet pipe communicating with said container above the liquid level thereof for conducting vapors from said housing; a cylinder; a piston reciprocating in said cylinder, said vapor outlet pipe communicating with said cylinder at opposite sides of said piston; and a check valve in said vapor outlet pipe and said cylinder at each side of said piston for controlling the flow of fluid into said cylinder upon movement of said piston in either direction relatively to said cylinder; a pair of outlet pipes each communicating with said cylinder at opposite sides of said piston; a check valve at each of said outlet pipes for controlling the flow of fluid outwardly from said cylinder upon movement of said piston in either direction, said outlet delivery pipes communicating with said inlet delivery pipe which communicates with said valve housing.

5. In an air cooling device of the class described, comprising: a housing having an air inlet and an air outlet; a container positioned within said housing adapted for the reception of a volatile liquid; a manifold; a plurality of tubes establishing communication with said manifold and with said container through the bottom thereof; a valve housing positioned within said container; an outlet conduit communicating with said valve housing for conducting liquid to said manifold; an inlet conduit for conducting liquid into said valve housing; a valve in said housing; a rockable beam adapted upon rocking in one direction for opening said valves; and a float mounted on said beam and adapted upon rising of liquid in said container to a predetermined height for rocking said beam in the opposite direction to close said valve; and a vapor outlet pipe communicating with said container above the liquid level thereof for conducting vapors from said housing; a cylinder; a piston reciprocating in said cylinder, said vapor outlet pipe communicating with said cylinder at opposite sides of said piston; and a check valve in said vapor outlet pipe and said cylinder at each side of said piston for controlling the flow of fluid into said cylinder upon movement of said piston in either direction relatively to said cylinder; a pair of outlet pipes each communicating with

with said cylinder at opposite sides of said piston; a check valve at each of said outlet pipes for controlling the flow of fluid outwardly from said cylinder upon movement of said piston in either direction, said outlet delivery pipes communicating with said inlet delivery pipe which communicates with said valve housing; a coolant container; a coil in said coolant container, said coil being connected to said outlet delivery pipes which communicate with said cylinder and to the pipe which communicates as an inlet pipe to said valve housing.

6. In an air cooling device of the class described, comprising: a housing having an air inlet and an air outlet; a container positioned within said housing adapted for the reception of a volatile liquid; a manifold; a plurality of tubes establishing communication with said manifold and with said container through the bottom thereof; a valve housing positioned within said container; an outlet conduit communicating with said valve housing for conducting liquid to said manifold; an inlet conduit for conducting liquid into said valve housing; a valve in said housing; a rockable beam adapted upon rocking in one direction for opening said valve; and a float mounted on said beam and adapted upon rising of liquid in said container to a predetermined height for rocking said beam in the opposite direction to close said valve; and a vapor outlet pipe communicating with said container above the liquid level thereof for conducting vapors from said housing; a cylinder; a piston reciprocating in said cylinder, said vapor outlet pipe communicating with said cylinder at opposite sides of said piston; and a check valve in said vapor outlet pipe and said cylinder at each side of said piston for controlling the flow of fluid into said cylinder upon movement of said piston in either direction relatively to said cylinder; a pair of outlet pipes each communicating with said cylinder at opposite sides of said piston; a check valve at each of said outlet pipes for controlling the flow of fluid outwardly from said cylinder upon movement of said piston in either direction, said outlet delivery pipes communicating with said inlet delivery pipe which communicates with said valve housing; a coolant container; a coil in said coolant container, said coil being connected to said outlet delivery pipes which communicate with said cylinder and to the pipe which communicates as an inlet pipe to said valve housing; and a cooling coil communicating with said coolant container for conducting liquid therefrom into the path of air passing through said housing.

7. In an air cooling device of the class described, comprising: a housing having an air inlet and an air outlet; a container positioned within said housing adapted for the reception of a volatile liquid; a manifold; a plurality of tubes establishing communication with said manifold and with said container through the bottom thereof; a valve housing positioned within said container; an outlet conduit communicating with said valve housing for conducting liquid to said manifold; an inlet conduit for conducting liquid into said valve housing; a valve in said housing; a rockable beam adapted upon rocking in one direction for opening said valve; and a float mounted on said beam and adapted upon rising of liquid in said container to a predetermined height for rocking said beam in the opposite direction to close said valve; and a vapor outlet pipe communicating with said container above the liquid level thereof for conducting vapors from said housing; a cylinder; a piston reciprocating in said cylinder, said vapor outlet pipe communicating with said cylinder at opposite sides of said piston; and a check valve in said vapor outlet pipe and said cylinder at each side of said piston for controlling the flow of fluid into said cylinder upon movement of said piston in either direction relatively to said cylinder; a pair of outlet pipes each communicating with

above the liquid level thereof for conducting vapors from said housing; a cylinder; a piston reciprocating in said cylinder, said vapor outlet pipe communicating with said cylinder at opposite sides of said piston; and a check valve in said vapor outlet pipe and said cylinder at each side of said piston for controlling the flow of fluid into said cylinder upon movement of said piston in either direction relatively to said cylinder; a pair of outlet pipes each communicating with said cylinder at opposite sides of said piston; a check valve at each of said outlet pipes for controlling the flow of fluid outwardly from said cylinder upon movement of said piston in either direction, said outlet delivery pipes communicating with said inlet delivery pipe which communicates with said valve housing; a coolant container; a coil in said coolant container, said coil being connected to said outlet delivery pipes which communicate with said cylinder and to the pipe which communicates as an inlet pipe to said valve housing; and a cooling coil communicating with said coolant container for conducting liquid therefrom into the path of air passing through said housing; a rockable arm for reciprocating said piston; a sleeve, said arm projecting through said sleeve; a pivot pin for pivotally mounting said arm intermediate its ends on said sleeve at various positions thereon.

8. In an air cooling device of the class described, comprising: a housing having an air inlet and an air outlet; a container positioned within said housing adapted for the reception of a volatile liquid; a manifold; a plurality of tubes establishing communication with said manifold and with said container through the bottom thereof; a valve housing positioned within said container; an outlet conduit communicating with said valve housing for conducting liquid to said manifold; an inlet conduit for conducting liquid into said valve housing; a valve in said housing; a rockable beam adapted upon rocking in one direction for opening said valve; and a float mounted on said beam and adapted upon rising of liquid in said container to a predetermined height for rocking said beam in the opposite direction to close said valve; and a vapor outlet pipe communicating with said container above the liquid level thereof for conducting vapors from said housing; a cylinder; a piston reciprocating in said cylinder, said vapor outlet pipe communicating with said cylinder at opposite sides of said piston; and a check valve in said vapor outlet pipe and said cylinder at each side of said piston for controlling the flow of fluid into said cylinder upon movement of said piston in either direction relatively to said cylinder; a pair of outlet pipes each communicating with said cylinder at opposite sides of said piston; a check valve at each of said outlet pipes for controlling the flow of fluid outwardly from said cylinder upon movement of said piston in either direction, said outlet delivery pipes communicating with said inlet delivery pipe which communicates with said valve housing; a coolant container; a coil in said coolant container, said coil being connected to said outlet delivery pipes which communicate with said cylinder and to the pipe which communicates as an inlet pipe to said valve housing; and a cooling coil communicating with said coolant container for conducting liquid therefrom into the path of air passing through said housing; a rockable arm for reciprocating said piston; a sleeve, said arm projecting through said sleeve; a pivot pin for pivotally mounting said arm intermediate its ends on said sleeve at various positions thereon; and means for rocking said arm in opposite directions, said tubes communicating with said manifold being constricted intermediate their ends; and a radiating pin mounted on each of said tubes at the constricted portion.

60

ciprocating said piston; a sleeve, said arm projecting through said sleeve; a pivot pin for pivotally mounting said arm intermediate its ends on said sleeve at various positions thereon; and means for rocking said arm in opposite directions.

9. In an air cooling device of the class described, comprising: a housing having an air inlet and an air outlet; a container positioned within said housing adapted for the reception of a volatile liquid; a manifold; a plurality of tubes establishing communication with said manifold and with said container through the bottom thereof; a valve housing positioned within said container; an outlet conduit communicating with said valve housing for conducting liquid to said manifold; an inlet conduit for conducting liquid into said valve housing; a valve in said housing; a rockable beam adapted upon rocking in one direction for opening said valve; and a float mounted on said beam and adapted upon rising of liquid in said container to a predetermined height for rocking said beam in the opposite direction to close said valve; and a vapor outlet pipe communicating with said container above the liquid level thereof for conducting vapors from said housing; a cylinder; a piston reciprocating in said cylinder, said vapor outlet pipe communicating with said cylinder at opposite sides of said piston; and a check valve in said vapor outlet pipe and said cylinder at each side of said piston for controlling the flow of fluid into said cylinder upon movement of said piston in either direction relatively to said cylinder; a pair of outlet pipes each communicating with said cylinder at opposite sides of said piston; a check valve at each of said outlet pipes for controlling the flow of fluid outwardly from said cylinder upon movement of said piston in either direction, said outlet delivery pipes communicating with said inlet delivery pipe which communicates with said valve housing; a coolant container; a coil in said coolant container, said coil being connected to said outlet delivery pipes which communicate with said cylinder and to the pipe which communicates as an inlet pipe to said valve housing; and a cooling coil communicating with said coolant container for conducting liquid therefrom into the path of air passing through said housing; a rockable arm for reciprocating said piston; a sleeve, said arm projecting through said sleeve; a pivot pin for pivotally mounting said arm intermediate its ends on said sleeve at various positions thereon; and means for rocking said arm in opposite directions, said tubes communicating with said manifold being constricted intermediate their ends; and a radiating pin mounted on each of said tubes at the constricted portion.
